(57) **CLAIM**

The ornamental design for the molded foam sofa middle section with discrete backrest, as shown and described.

DESCRIPTION

FIG. 1 is a front perspective view of a molded foam sofa middle section with a discrete backrest.

FIG. 2 is a front view thereof.

FIG. 3 is a right side view thereof.

FIG. 4 is a left side view thereof.

FIG. 5 is a back view thereof; and,

FIG. 6 is a top view thereof.

Elements of the drawings shown in dashed lines are for illustrative purposes only and form no part of the claimed design.
